UNITED STATES PATENT OFFICE.

THOMAS E. SPENCER, OF WETASKUVIN, ALBERTA, CANADA.

BOMB-THROWER.

1,342,357.

Specification of Letters Patent.

Patented June 1, 1920.

Application filed December 16, 1918. Serial No. 266,979.

To all whom it may concern:

Be it known that I, THOMAS E. SPENCER, a subject of the King of Great Britain, residing at Wetaskuvin, in the Province of Alberta and Dominion of Canada, have invented new and useful Improvements in Bomb-Throwers, of which the following is a specification.

This invention relates to bomb throwers or bomb throwing machines of the portable type, the object in view being to provide a portable bomb throwing machine by means of which bombs or grenades or the like may be thrown to a great distance with safety to the operator of the machine. The improvement relates particularly to the means for setting, holding and releasing the bomb throwing member, this being accomplished with ease and precision.

20 A further object of the invention is to provide means for increasing or diminishing the elevation of the bomb throwing machine so as to vary the range thereof.

With the above and other objects in view, 25 the invention consists in the novel construction, combination and arrangement herein illustrated, described and claimed.

In the accompanying drawings;

Figure 1 is a side elevation of the bomb 30 thrower.

Fig. 2 is a fragmentary vertical longitudinal section on an enlarged scale showing the barrel and plunger.

Fig. 3 is a vertical cross section on the 35 line 3—3 of Fig. 1.

Fig. 4 is a vertical cross section on the line 4—4 of Fig. 1.

Fig. 5 is a cross section on the line 5—5 of Fig. 1.

40 The bomb thrower contemplated in this invention, in the preferred embodiment thereof, comprises a barrel 1 which constitutes means for guiding the bomb or grenade and the bomb throwing or projecting member. The member 1 comprises a channel 2 in which is slidably mounted a plunger or bomb projecting or throwing member 3 having at the rear end thereof a block or head 4 which is slidable in longitudinal 45 guideways 5 formed in the sides of the channeled member 1 and provided adjacent to its forward extremity with an upstanding bomb holding shoulder or clip 6 in front of which the bomb or grenade is 50 placed while resting upon the barrel or guiding member 1.

The member 1 is pivotally mounted at 7 upon a frame 8 which normally assumes an inclined position as shown in Fig. 1. The frame 8 is supported by carrying wheels 9 60 from which supporting standards 10 extend upwardly to the frame 8. Braces 11 are interposed between the lower ends of the uprights 10 and the frame 8. Extending upwardly from the frame 8 are oppositely 65 arranged guiding members 12 between which is arranged the rear end portion of the barrel or guiding member 1. Extending rearwardly from the member 1 is a lever 13 for raising or lowering the rear end of 70 the member 1 and correspondingly elevating or depressing the forward end thereof to vary the range of the bomb thrower. Attached to the lever 13 is a latch 14 adapted to engage a curved rack 15 extending up- 75 wardly from the frame 8, thus enabling the range to be fixed when properly adjusted.

16 designates a plunger retracting lever which is pivotally mounted at 17 on the 80 frame 8. The lever 16 carries a spring pressed thumb latch 18 which engages an arcuate rack 19 on the frame 8 thus enabling the lever 16 to be held in any desired position to which it may be adjusted. The lever 85 16 carries on the forward face thereof a slotted or grooved guide 20 to which is mounted a block or guide 21 having a jointed connection with the rear extremity of a plunger retracting rod 22. The rod 22 is 90 attached at its forward extremity to a runner 23 which is movable longitudinally of the guide ways 5 hereinabove referred to. The runner 23 carries a trigger 24 which is adapted to engage the block or head 4 95 at the rear end of the plunger hereinabove referred to. Attached to the trigger 24 is a trigger operating rod 25 which extends rearwardly through a guide 26 which is provided with a suitable operating knob or 100 handle 27 within convenient reach of the operator. As the runner 23 is drawn rearwardly by means of the lever 16, the trigger operating rod 25 is also drawn rearwardly 105 so as to be in a position convenient for immediate operation. Plunger actuating springs 28 are arranged at opposite sides of the barrel or guiding member 1, being attached at their rear extremities to the block or head 4 and being attached at their forward extremities to the barrel or guiding member 1 adjacent to the forward end of the 110

latter. Suitable handles 29 extend from the member 1 oppositely and are employed for shifting the bomb thrower from place to place.

5 From the foregoing description, when taken in connection with the accompanying drawings, it will now be seen that the bomb thrower may be readily and quickly shifted from place to place, the elevation of the barrel or guiding member may be quickly adjusted according to the desired range, and by means of the lever 16, the bomb throwing plunger may be quickly retracted to the initial point of its throw. The bomb 10 or grenade is in place in front of the actuating shoulder or trip 6 after which the operator throws the trigger 24 forward to releasing position by means of the actuating rod 25, thereby releasing the plunger and 15 projecting the bomb from the machine.

20 I claim:—

1. A bomb thrower comprising a spring actuated bomb throwing plunger, guiding means for said plunger, a frame supporting said guiding means, a plunger retracting lever fulcrumed on said frame, lever holding means, a plunger retracting runner connected with said lever, and a plunger holding and releasing trigger carried by and movable with said runner.

2. A bomb thrower comprising a spring actuated bomb throwing plunger, guiding

means for said plunger, a frame supporting said guiding means, a plunger retracting lever fulcrumed on said frame, lever holding means, a plunger retracting runner connected with said lever, a trigger, a trigger operating rod extending rearwardly from said trigger, and guiding means for said rod.

3. A bomb thrower comprising a spring actuated bomb throwing plunger, guiding means for said plunger, a frame supporting said guiding means, a plunger retracting lever fulcrumed on said frame, lever holding means, a plunger retracting runner connected with said lever, a plunger holding and releasing trigger carried by and movable with said runner, and a runner retracting rod having a slidable connection with 40 said lever.

4. A bomb thrower comprising a spring actuated bomb throwing plunger, guiding means for said plunger, a frame supporting said guiding means, a plunger retracting lever fulcrumed on said frame, lever holding means, a plunger retracting runner connected with said lever, a plunger holding and releasing trigger carried by and movable with said runner, and means for varying 45 the elevation of said guiding means.

55 In testimony whereof I affix my signature.

60 THOMAS E. SPENCER.
